INDUCTIVE WIRELESS-TELEPHONE SYSTEM FOR RAILROADS AND THE LIKE.

1,242,877.

Specification of Letters Patent.

Patented Oct. 9, 1917.

Application filed August 14, 1916. Serial No. 114,684.

To all whom it may concern:

Be it known that we, VICTOR GABRIEL WERNER and KARL HJALMAR WARFVINGE, subjects of the King of Sweden, residing at 5 Stockholm, in the Kingdom of Sweden, have invented a new and useful Improvement in Inductive Wireless-Telephone Systems for Railroads and the like, of which the following is a specification.

10 This invention relates to an improvement in an inductive wireless telephone system for telephoning between moving railroad trains, or other vehicles, or between such and railroad stations or other stationary places. In 15 the accompanying drawing, Figure 1 represents in a curve, the relation between current and frequency. Fig. 2 is a diagram of the circuits of the apparatus carried on the moving vehicle. Fig. 3 is a diagram of 20 another such circuit. The said system consists of an inductive connection between a closed movable induction circuit and a closed stationary induction circuit, the former of which is arranged on the train, 25 and the latter of which is formed by a single or a double aerial conductor along the track, which conductor is connected to a fixed station. The inductive part of the movable circuit preferably consists of an 30 induction frame comprising one or several turns of an insulated conductor and inclosing the greatest possible induction area, or it may consist of several such induction frames.

35 The purpose of the present invention is to increase the sensitivity and the inductive effect of the movable induction circuit by making the same as a compound oscillation circuit possessing a plurality of natural oscillation periods of its own. The tuning of 40 the circuit is preferably made so that the frequencies of these natural oscillations are uniformly distributed over the range of frequency of the most important speech oscillations. The intervals between the natural 45 frequencies should not be greater than is necessary from practical reasons with regard to the fact that the arrangement becomes complicated in the same degree as the 50 number of branches of the compound circuit is increased. The peaks of the resonance curve should thus be brought to flow together and become leveled as much as possible, so that the curve may obtain about the 55 appearance illustrated in Fig. 1. 1, 2, 3, 4,

and 5 denote the frequencies of the natural oscillations; the ordinates are proportional to the induction in the circuit. The damping of the circuit also contributes to the flattening of the upper part of the resonance 60 curve. The damping should be effected as much as possible by useful resistance (of the microphone or of the receiver). Under such conditions the tuning has no detrimental effect on the articulation of the speech, but 65 offers a possibility of materially increasing the number of turns of the induction frame without the resistance to alternating current in the induction circuit being increased in a 70 corresponding degree.

75 Fig. 2 shows an example of a compound oscillatory circuit having five natural oscillation periods of its own. L is the induction frame, L' one winding of an induction coil, the other winding of which may be connected by means of the switch S either with the microphone M and its source B of current, or with the receiver H. The tuned branches 1, 2, 3, 4, and 5, each of which includes an inductive reactance L_1 , L_2 , etc., 80 and a condenser C_1 , C_2 , etc., or only a condenser C_5 , cause in the resonance circuit an equal number of natural oscillations of its own. A change in the self-induction or in the capacity of one branch causes, primarily, 85 a change of the natural oscillation of this branch, but influences also the other branches to some extent.

90 Fig. 3 shows an embodiment in which one of the natural frequencies—preferably the mean frequency of the range of speech oscillations—may be made independent of the other. This is effected by tuning the branch L L' C' and the branch $L_1 C_1$ to the said mean frequency n_0 in such manner that 95

$$\frac{1}{(2\pi n_0)^2} = (L \div L')C' = L_1 C_1.$$

Otherwise the arrangement according to 100 Fig. 3 is analogous to that shown in Fig. 2 with the difference only that one of the branches may include an inductive reactance only, without a condenser.

105 The stationary circuit may also be tuned to the speech oscillations in the same manner as described above in respect of the movable circuit. On account of the appreciable ohmic resistance of the line, however, this tuning is as a rule considerably less efficient than that described above.

110

The invention may, of course, also be used on vessels, for instance in canal and river traffic.

We claim:

- 5 In an inductive wireless telephone system for railroads, the combination of a stationary circuit consisting of an aerial conductor along the railroad track and connected to a fixed telephone station, and a circuit on the
- 10 train comprising a microphone, a receiver, and a source of electrical energy, said circuits being in inductive relation to each

other and one of said circuits comprising combined resonance circuits with a plurality of natural oscillations of their own tuned in 15 such manner that they are uniformly distributed over the most important range of frequency of the speech oscillations, for the purpose of increasing the sensitivity of the circuit to oscillations within this range, substantially as described.

VICTOR GABRIEL WERNER.
KARL HJALMAR WARFVINGE.
